UNITED STATES PATENT OFFICE.

FREDERICK WILLIAM CAMPBELL, OF BELFAST, IRELAND.

DESIGN FOR A TABLE-CLOTH OR SERVIETTE.

44,357.

Specification for Design.

Patented July 22, 1913.

Application filed April 11, 1913. Serial No. 760,554. Term of patent 14 years.

To all whom it may concern:

Be it known that I, FREDERICK WILLIAM CAMPBELL, a subject of the King of Great Britain and Ireland, and residing at Belfast, Ireland, have invented a new, original, and ornamental Design for Table-Cloths or Serviettes, of which the following is a specification, reference being had to the accompanying drawing, forming part thereof.

The figure is a plan view of part of a table cloth showing my new design.

I claim:

The ornamental design for a table cloth or serviette, as shown.

FREDK. WILLIAM CAMPBELL.
